UNITED STATES PATENT OFFICE.

WILLIAM R. DUTEMPLE, OF PROVIDENCE, R. I., ASSIGNOR OF TWO-THIRDS
TO GEORGE C. CASE AND ASAHEL B. CASE, BOTH OF SAME PLACE.

EAR-RING FASTENER.

SPECIFICATION forming part of Letters Patent No. 280,726, dated July 3, 1883.

Application filed April 14, 1883. (No model.)

To all whom it may concern:

Be it known that I, WILLIAM R. DUTEMPLE, a citizen of the United States, residing at Providence, in the county of Providence and State of Rhode Island, have invented certain new and useful Improvements in Ear-Ring Fasteners; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

My invention relates to the manner of attaching ear ornaments; and it consists of a fastener made of wire, bent to form a half-coil, and provided with an elongated point.

Figure 1 represents an ear ornament with fastener complete, enlarged size. Fig. 2 is an end view of the same.

To the back of the ornament A is secured, by solder or other suitable means, the fastener B, which is made of wire, the straight or shank

portion a being of suitable length to extend 25 through the lobe of the ear. The wire is bent to form a half-coil, a', which terminates in an elongated point, a''.

The fastener is attached to the ear by inserting the point a'' into and twisting it through 30 the aperture of the ear-lobe, the half-coil a' serving to retain the fastener in position.

The fastener is detached by reversing the above-described operation of attaching.

Having thus described my invention, what I 35 claim as new, and desire to secure by Letters Patent, is—

The combination, with an ear ornament, of the fastener B, the latter consisting of the shank a, half-coil a', and elongated point a'', 40 the whole arranged and adapted for use as and for the purpose specified.

In testimony whereof I have affixed my signature in presence of two witnesses.

WM. R. DUTEMPLE.
